(57) **CLAIM**

The ornamental design for a laser level, as shown and described.

DESCRIPTION

FIG. 1 is a front perspective view of a laser level showing our new design;

FIG. 2 is a top plan view thereof;

FIG. 3 is a left side view thereof;

FIG. 4 is a bottom plan view thereof;

FIG. 5 is a front view thereof;

FIG. 6 is a rear view thereof; and,

FIG. 7 is a left side view thereof.

The broken lines shown are included for the purpose of illustrating portions of the laser level and form no part of the claimed design.
